UNITED STATES PATENT OFFICE

139,090

DESIGN FOR A COMBINATION BATHROOM UNIT

Frank J. Zavada, Pittsburgh, Pa.

Application September 1, 1943, Serial No. 111,040

Term of patent 14 years

(Cl. D4—4)

To all whom it may concern:

Be it known that I, Frank J. Zavada, a citizen of the United States, residing at Pittsburgh, in the county of Allegheny and State of Pennsylvania, have invented a new, original, and ornamental Design for a Combination Bathroom Unit, of which the following is a specification, reference being had to the accompanying drawing, forming part thereof.

tion bathroom unit showing my new design, a portion of two walls being broken to show the interior of the unit; and

Figure 2 is a diagrammatic perspective view, on a reduced scale, of the unit showing the door closed and the walls complete.

I claim:

The ornamental design for a combination bathroom unit, as shown.

FRANK J. ZAVADA.
